ABSTRACT

The embodiment of the invention disclosed herein is directed to a scarifier assembly for use with an asphalt concrete roadway refinisher. The scarifier has a support frame for movement in a given direction over the road surface being refinished, and the plurality of scarifying blades secured to the support frame for selective upward and downward movement to engage the road surface when in the down position during the scarifying operation for digging up and excavating the road surface after it is heated with radiant heat energy. The scarifier assembly is urged against the heated road surface by the air bags which force the scarifying blades deep into the asphalt pavement. The scarifying blades are secured by shear pin means which can be easily replaced when necessary.

SCARIFIER FOR USE WITH ASPHALT CONCRETE ROADWAY REFINISHING APPARATUS

BACKGROUND OF THE INVENTION

This invention relates generally to improvements in structure and apparatus roadway resurfacing machinery, and more particularly to a new and improved scarifying assembly which forms one of the work stations of the roadway resurfacing machine.

This invention deals with substantial useful improvements in my earlier filed patent application, entitled "Road Surfacing Apparatus" and which has issued as U.S. Pat. No. 3,361,042. This patent discloses means for quickly and inexpensively resurfacing roadways which are made of asphalt concrete material and the like. The apparatus may be in the order of about 8 to 12 feet wide and 40 to 50 feet long and move along the roadway at a relatively slow rate so that during a single continuous pass the old road surface in front of the machine is heated and ultimately excavated as the machine moves thereover and a refinished road surface is formed at the rear of the machine. All of the old road surface material is recycled into the new road surface thus formed. A distinct advantage of repaving apparatus of the type disclosed in my earlier patent is that the finished repaved road surface is substantially immediately available for traffic within a matter of minutes after the completion of the road surface.

Heating apparatus as disclosed in my co-pending application Ser. No. 369,775 filed June 13, 1973, substantially increases the efficiency of heating the road surface as the machine moves thereacross. Therefore, scarifying equipment can excavate the heated asphalt to a greater depth so that more complete mixing of filler asphalt is obtained.

Heretofore, asphalt concrete roadway repaving machines have been relatively long because of the necessity of the plurality of successive work stations along the machine. Furthermore, to effect adequate scarifying of the old road surface, several scarifying stations had to be used.

SUMMARY OF THE INVENTION

Accordingly, it is an object of this invention to provide a new and improved scarifying assembly to be positioned adjacent radiant heating elements of an asphalt concrete roadway repaving machine which can excavate the road surface to a sufficient depth, thereby eliminating the need of two or more scarifying assemblies.

Still another object of this invention is to provide a new and improved scarifying assembly for use with asphalt concrete roadway repaving machines which can be repaired quickly and easily should the scarifying blades inadvertently become dislodged from their fixed position.

Still another object of this invention is to provide a new and improved scarifying assembly which receives pressure from air bags so as to urge the scarifying blades directly downwardly against the road surface to be excavated.

Many other objects, features and advantages of this invention will be more fully realized and understood from the following detailed description when taken in conjunction with the accompanying drawings wherein like reference numerals throughout the various views

of the drawings are intended to designate similar elements or components.

BRIEF DESCRIPTION OF THE DRAWINGS

- 5 FIG. 1 is a side elevational view of a road repaving machine wherein the scarifying assembly of this invention is utilized;
- 10 FIG. 2 is a fragmentary detailed showing of the scarifying assembly of this invention;
- 15 FIG. 3 is a fragmentary perspective view of the scarifying assembly of this invention;
- 20 FIG. 4 is a fragmentary side view showing the pivotal shear arrangement for the scarifying blades of the scarifying assembly of this invention;
- 25 FIG. 5 is a front view of the scarifying blades of FIG. 4;
- 30 FIG. 6 is a top view showing the staggered row arrangement of the scarifying blades of the scarifying assembly of this invention;
- 35 FIG. 7 is a diagrammatic representation showing the control valve manifold arrangement for controlling a plurality of air bags to urge the scarifying blades into contact with the road surface in accordance with the principles of this invention; and
- 40 FIG. 8 is a top view illustrating the transverse arrangement of a plurality of support arm members, each having a group of scarifying blades associated therewith to be urged into contact with the road surface being repaved.

DETAILED DESCRIPTION OF THE ILLUSTRATED EMBODIMENT

Referring now to FIG. 1, there is seen an elevational view of a road resurfacing machine designated generally by reference numeral 10, and wherein the scarifying assembly of this invention is utilized. The road resurfacing machine 10 has a plurality of large pneumatic tires 13 having sufficient contact area with the road surface so that the weight of the large machine is distributed uniformly over the road surface so as not to deform the newly paved roadway passing therebeneath. As the road resurfacing machine 10 moves forward over a damaged road surface, the front end of the machine will heat up the road surface to a depth of approximately 1 to 2 inches or more and an intermediate stage of the machine, where at the scarifying assembly of this invention is located, will dig up the road surface. The quantity of old road surface now forming loose pavement has a quantity of new asphalt material added therewith to build up the road surface to the previous height or to a height greater than the old road surface, if desired. Generally, the quantity of new asphalt material added to the old road surface is just enough to replace those quantities which have been depleted as a result of pot holes or the like. The rate of travel of the machine may be on the order of 8 to 20 feet per minute thereby providing a completely reconstructed road surface upon which traffic can travel substantially immediately after the road surface has been formed.

60 A quantity of new asphalt material 14 is delivered via a truck or other suitable transport means 16 into a hopper or receptacle 17 located at the front of the road resurfacing machine 10. A conveyor assembly 18 along the top portion of the frame support of the machine transports the new asphalt material from the hopper to one or more various work stations along the machine. A control station designated generally by reference nu-

meral 19 is located intermediate the machine, and an operator is stationed at this point to control the direction of travel of the machine, as well as the rate of travel thereof. The operator also controls the various functions to be accomplished during the travel of the machine. For example, the operator will control the amount of heat applied to the road surface by various heating units and may control the amount of pressure applied to the scarifying assembly to dig up the old road surface to the desired depth. One or more diesel engines 20 are mounted at the rear portion of the machine and include various control panel arrangements 20a which may be used to operate hydraulic pumps or compressors or the like. The wheels 13 are motorized preferably by independent hydraulic motors operated by hydrostatic hydraulic supply pumps controlled by the diesel engines and control panel 20a. However, it will be understood that other drive means than those described here may be incorporated.

A plurality of fuel tanks 21 are mounted on top of the support frame and designated generally by reference numeral 22 and are used to carry fuel supplies for both the diesel engine and the radiant heating apparatus 24 which is located at the forward end of the machine. While a single radiant heating apparatus 24 is disclosed herein, previous disclosures of this machine in related patent applications disclosed two radiant heating apparatus. Therefore, it will be understood that one, two, or more heating units may be utilized without departing from the spirit and scope of this invention. One or more of the fuel tanks 21 may be filled with diesel fuel while one or more of the other fuel tanks may be filled with pentane fuel for operating the radiant heating burners within the heater 24. The manner in which the road resurfacing machine 10 operates is more fully disclosed in my related U.S. Pat. No. 3,361,042; and no further details of description of operation is deemed necessary herein. However, the details necessary for a complete understanding of this invention are understood to be incorporated herein from the above-mentioned patent.

The heating apparatus 24 includes a heating chamber 28 facing downwardly to be positioned immediately over the road surface to be repaved so that the road surface can be heated to a depth of approximately two inches more or less so that the asphalt of the concrete pavement can be adequately softened to be excavated by the scarifying apparatus of this invention. After the heating of the road surface is accomplished, a scarifying assembly 25, positioned behind the heating apparatus, will excavate the road surface to a desired depth. The scarifying apparatus 25 is of new and novel design and is substantially more efficient than scarifying apparatus heretofore utilized.

FIG. 2 illustrates a side elevational view of the scarifying apparatus 25 and shows only a portion of a support frame 30 adapted to be moved over the road surface in a given direction as indicated by the arrow 31. Positioned beneath the support frame 30 are a plurality of scarifying blades 32 which are formed in a plurality of sub-groups extending transversely across the direction of motion of the machine. Each of the sub-groups of scarifying blades 32 are secured to the free end of an arm member 33 tentatively secured by pin means 34 to a depending pull bar assembly 36 that raises and lowers by a motor driven drive screw mechanism designated generally by reference numeral 37. The drive screw mechanism 37 therefore is used to adjust the relative

position of the pull bar assembly 36 so that the arms 33 are maintained substantially in a parallel position over the road surface, thereby eliminating the possibility of bending of the arms under the forces of the scarifying operation.

Most advantageously, pressure applying means designated generally by reference numeral 38 are positioned beneath the support frame 30 and are in direct engagement with the free ends of the arms 33 so that downward pressure is applied directly to the scarifying blades during the scarifying operation. The pressure applying means 38 is secured to a pressure bar member 39 which also holds a plurality of air bags 40, each air bag engaging the free end of the associated arm member 33, as best seen in FIG. 8. While the number of arms and associated air bags is here illustrated as being 12, designated generally by reference numerals 33a, 33b, 33c, 33d, 33e, 33f, 33g, 33h, 33i, 33j, 33k and 33l and the air bags designated by 40a, 40b, 40c, 40d, 40e, 40f, 40g, 40h, 40i, 40j, 40k, and 40l, a detailed description of only a single support arm and air bag configuration will be given herein, it being understood that the same description applies to all other arms and air bags.

The pressure bar 38 is secured to the frame member 30 by pivot means 41, located at each end thereof so that the pressure bar can be aligned with the inclination of the road surface, if desired. The pressure bar structure 38 is moved upwardly and downwardly relative to the support frame 30 by a drive motor mechanism 42 drivingly connected to a threaded shaft 43 which, in turn, moves the pressure bar upwardly and downwardly relative to the support frame. Once the scarifying blades are in contact with the road surface, high pressure for effecting excavation of the road surface is obtained from the air bag 40 which has an air line 44 connected thereto. The air line 44 applies pressure to the bag from a regulated air supply within a manifold, to be described in more detail herein below.

Positioned immediately behind the scarifying blades 32 and slightly to the outside thereof are a pair of joint cutting blades which remove the excess mix of asphalt concrete from the seam formed along the side of the machine. There is one of these joint cutting blades 46 on each side of the machine and is adjustable by a pair of link members 47 and 48 connected to a boss 49 and to a support arm 50. The adjustment is made by a threaded shaft 51. Preferably the lower edge surface 46a of the joint cutting blade is supplied with a weld bead of hard surfacing metal.

The excavated asphalt concrete is here designated generally by reference numeral 52 and is made level by a leveling blade 53 which rotates about a central axis 54 by suitable side border means, not shown. The leveling blade 53 is adjustable upwardly and downwardly by suitable means indicated generally by reference numeral 56. Therefore, the level of loose asphalt concrete is maintained uniform across the width of the machine prior to compressing the same into a compact road surface.

When pressure from within the air bag 40 is removed each of the arm members 33 is biased upwardly by a leaf spring member 57 which has one end thereof secured thereto the pull bar 36 and the other end thereof placed beneath the pad element 58 welded to the underside of the arm 53. FIG. 3 clearly illustrates the type of construction of each of the arm members 33, they being all substantially the same across the machine.

The arm member 33 is formed by a pair of spaced apart steel channel members 59 and 60 with the tab member 58 welded therebetween and the leaf spring 57 passes through the space between the channel members to engage the pad, as seen in FIG. 3. This feature of construction is also seen in FIG. 8.

The free end of the arm members 33 are provided with upper and lower plates 60 and 61, respectively, to form a substantially rigid box type construction to support the group scarifying blades secured thereto. The scarifying blade configuration is best illustrated in FIG. 6 which shows them arranged in rows 63, 64 and 65 which are staggered relative to one another, as seen in the drawing, so that the average spacing between scarifying blades is relatively small when considering the closest adjacent blade of a next row but which allows sufficient space between the blades of a given row so that excavated asphalt concrete material can easily flow through the scarifying apparatus to the leveling wheel 53. This arrangement eliminates the usual build-up of asphalt material in front of the scarifying blades and provides for a more uniform admixture to be produced.

FIGS. 4 and 5 illustrate the details of construction of the scarifying blades secured to the free end of the support arms 33. Each of the scarifying blades are here designated by reference numeral 70 and are secured between a pair of parallel spaced apart support plates 71 and 72. The scarifying blades 70 are held in position between the support plates 71 and 72 by a pair of bolt members 73 and 74, the bolt member 73 being of a larger diameter than the bolt member 74. Also the bolt member 74 is of a material that will shear under a predetermined amount of force so that should the scarifying blades 70 inadvertently engage an immovable structure in the road surface, such as a manhole, the smaller diameter bolt member 74 will shear and the scarifying blade will pivot about the larger diameter bolt member 73, as illustrated in phantom lines in FIG. 4. The repair and maintenance of this type of structure is relatively simple in that it only requires a new shear bolt to be inserted through the plate members 71 and 72 and the scarifying blade 70. The plate members are secured to the bottom of the plate 61 by suitable welding techniques and are held by welds 74. The lowermost leading edge of each of the scarifying blades 70 is provided with a hard material insert 76, such as tungsten carbide or the like.

FIG. 8 clearly illustrates the arrangement of the support arms 33 together with their groups of scarifying blades 32 and associated air bags positioned between the ends of the arm and the pressure bar 38. In this Figure, it will be noted that the endmost arm members 33a and 331 together with their associated scarifying blades 32a and 321 receive a different amount of pressure than do the scarifying blades and arms 33b through 33k. One reason for the additional force is the use of the joint cutting blades 46 at these locations. This is achieved by connecting the air bags 40a and 401 together and to one flow control manifold and connecting the air bags 40b through 40k to another flow control manifold.

The manifold arrangement to achieve proper control of air pressure to the air bags and 401 is illustrated in FIG. 7. Here a manifold unit 80 is divided into two manifold sections, 81 and 82, which are each individually controlled by separate pressure regulator units 83

and 84, respectively. The pressure regulators 83 and 84 are fed from a common pressure line 86. It is sometimes desirable to apply more pressure to the endmost air bags 40a and 401 so as to effect a deeper penetration of scarifying of the road surfacing by the associated scarifying blades 32a and 321. Therefore, the manifold chamber 81 is maintained at a higher pressure than is the manifold chamber 82. The flow control valves associated with the manifold unit 80 are of the on/off or open/close type, each being designated generally by reference numeral 86. The output line 87 associated with each of the valves is connected directly to its associated air bag and will inflate the air bag to a pressure determined by the associated regulator 83 or 84. If it is desired to raise selected ones of the arm members 33a-33l, so as to bypass a manhole cover or the like, the air flow control valves 86 associated with the appropriate air bags 40 will be opened so that no pressure will be applied to the air bag, and the chamber within the air bag is opened to atmospheric pressure. Once the repaving apparatus has passed over the manhole cover the appropriate air bags are again inflated to the pressure desired by operating the flow control valve 86.

What has been described is a simple and efficient scarifying assembly to use in conjunction with road paving apparatus which substantially improves the scarifying operation so that only a single scarifying unit is now required on the apparatus. While a single specific embodiment of this invention has been illustrated herein, it will be understood that variations and modifications of the invention may be effected without departing from the spirit and scope of the novel concepts as set forth in the specification and claims.

The invention is claimed as follows:

1. A scarifier assembly for engagement with a road surface to excavate the road surface, comprising: a support frame adapted to be moved over the road surface in a given direction, a plurality of scarifying blade units secured to said support frame for separate selective upward and downward movement and positioned to have cutting tips thereof engageable with the road surface when in the down position during a scarifying operation, and a plurality of discrete yieldable fluid operated pressure applying means positioned beneath said support frame and directly over said plurality of scarifying blades to apply a downward pressure directly upon said scarifying blades during the scarifying operation.

2. The scarifier assembly for engagement with a road surface to excavate the road surface as set forth in claim 1 wherein said plurality of scarifying blade units comprise groups of blades in a row across said support frame, said row being transverse to the direction of travel of said support frame.

3. The scarifier assembly for engagement with the road surface to excavate the road surface as set forth in claim 1 wherein each of said discrete yieldable pressure units is an air bag.

4. The scarifier assembly for engagement with the road surface to excavate the road surface as set forth in claim 1 wherein each of said groups of scarifying blades is formed of three rows of three blades in each row aligned transversely to the direction of travel of said support frame and each row staggered from the other rows to allow excavated road material easily to pass through the scarifying blades as it travels in said given direction.

5. The scarifier assembly for engagement with the road surface to excavate the road surface as set forth in claim 1 further including fluid pressure control means for controlling the pressure produced by each of the said plurality of discrete yieldable pressure units, said pressure control means including means for controlling the fluid pressure produced by the two endmost discrete yieldable pressure units independent of the discrete yieldable units therebetween.

6. The scarifier assembly for engagement with the road surface to excavate the road surface as set forth in claim 5 wherein said discrete pressure units between said two endmost units are operated from a common pressure supply, and including valve means connected between said common pressure supply and said discrete yieldable pressure units, whereby selected ones of said pressure units can be deactivated.

7. The scarifier assembly for engagement with a road surface to excavate the road surface as set forth in Claim 1 wherein said scarifying blades include shear pin means for holding said scarifying blades in a fixed position during a scarifying operation and to permit rearward pivotal movement of said scarifying blade when a predetermined high shear pressure is exerted on said scarifying blade.

8. The scarifier assembly for engagement with a road surface to excavate the road surface as set forth in claim 1 further including joint cutting blade means positioned transversely outwardly of the endmost scarifying blades to remove road resurfacing material from the seam formed along the transverse edges of a repaved road surface to be formed.

9. The scarifier assembly for engagement with a road surface to excavate the road surface as set forth in claim 1 wherein said scarifying blades each include a cutting tip insert element of hardened metal.

10. A scarifier assembly for engagement with a road surface to excavate the road surface, comprising: a support frame adapted to be moved over the road surface in a given direction, a plurality of scarifying blades secured to said support frame for selective upward and downward movement and positioned to have cutting tips thereof engageable with the road surface when in the down position during a scarifying operation, yieldable pressure applying means positioned beneath said support frame and directly over said plurality of scarifying blades to apply a downward pressure directly upon said scarifying blades during the scarifying operation, a plurality of arm means each having one end pivotally secured to said support frame, said plurality of scarifying blades being arranged in groups, each group secured to the free end of an independent one of said plurality of arm means, a pressure beam secured to said support frame immediately above said free end of said arm means, and pressure bag means positioned between said pressure beam and said free end of said arm means to urge the scarifying blades into the road surface being excavated.

11. The scarifier assembly for engagement with the road surface to excavate the road surface as set forth in claim 10 further including a plurality of paired spaced apart support plates depending from said free end of said arm means, said scarifying blades being positioned between said support plates, a first fastener of predetermined diameter passing through said support plates and the upper end of said scarifying blade, a second fastener of a diameter less than said predetermined

diameter passing through said support plates and said scarifying blade immediately below said first fastener, whereby an excess of pressure applied to said scarifying blade will shear said second diameter fastener and pivot the scarifying blade about said first fastener.

12. The scarifier assembly for engagement with a road surface to excavate the road surface as set forth in claim 11 further including a plurality of spring means for automatically biasing said arms upwardly to raise the scarifying blade from the road surface when the pressure applying units are deactivated.

13. The scarifier assembly for engagement with a road surface to excavate the road surface as set forth in claim 12 wherein said spring means are a plurality of discrete leaf springs for each one of said arm means.

14. A road scarifier apparatus for excavating a road surface comprising in combination: heating means for movement over the road surface to soften asphalt concrete pavement forming the road surface, a support frame for supporting said heating means, said support frame adapted to be moved over the road surface in a given direction, a plurality of scarifying blade units secured to said support frame behind said heating means for separate selective upward and downward movement and positioned to have cutting tips thereof engageable with the heated road surface when in the down position for excavating the road surface, and a plurality of discrete separately yieldable fluid operated pressure applying units positioned beneath said support frame and respectively directly over said plurality of scarifying blade units separately to apply a downward pressure directly upon the scarifying blade units during a scarifying operation.

15. The road scarifier apparatus for excavating a road surface as set forth in claim 14, further including fluid pressure control means for controlling the pressure produced by each of said yieldable plurality of discrete pressure units, said pressure control means including means for controlling the pressure produced by the two endmost discrete yieldable pressure units independent of the discrete pressure units therebetween.

16. The road scarifier apparatus for excavating a road surface as set forth in claim 15, wherein said discrete yieldable pressure units between said two endmost units are operated from a common pressure supply, and including valve means connected between said common pressure supply and said discrete yieldable pressure units, whereby selected ones of said pressure units can be de-activated.

17. The road scarifier apparatus for excavating a road surface as set forth in claim 14, wherein said scarifying blades include shear pin means for holding the scarifying blades in a fixed position during a scarifying operation and to permit rearward pivotal movement of the scarifying blades when a predetermined high shear pressure is exerted on the scarifying blades.

18. The road scarifier apparatus for excavating a road surface as set forth in claim 14 wherein each of said discrete pressure units is an air bag.

19. The road scarifier apparatus for excavating a road surface as set forth in claim 14, further including joint cutting blade means positioned transversely outwardly of the endmost scarifying blades to remove the road resurfacing material from the seam formed along the transverse edges of the repaved road surface formed by said apparatus.

20. The road scarifier apparatus for excavating a road surface as set forth in claim 14, wherein said scarifying blades each include a cutting tip insert element of hard metal.

21. A road scarifier apparatus for excavating a road surface comprising in combination: heating means for movement over the road surface to soften asphalt concrete pavement forming the road surface, a support frame for supporting said heating means, said support frame adapted to be moved over the road surface in a given direction, a plurality of scarifying blades secured to said support frame behind said heating means for selective upward and downward movement and positioned to have cutting tips thereof engageable with the heated road surface when in the down position for excavating the road surface, yieldable pressure applying means positioned beneath said support frame and directly over said plurality of scarifying blades for applying a downward pressure directly upon the scarifying blades during a scarifying operation, a plurality of arm means each having one end thereof pivotally secured to said support frame, said plurality of scarifying blades being arranged in groups, each group secured to the free end of an independent one of said plurality of arm means, a pressure beam secured to said support frame immediately above said free end of said arm means, and pressure bags positioned between said pressure beam and said free end of said arm means to apply pneumatic pressure between said pressure means and the end of said arm means to urge the scarifying blades into firm contact with the road surface being excavated.

22. The road scarifier apparatus for excavating a road surface as set forth in claim 21 further including

a plurality of paired spaced apart support plates depending from said free end of said arm means, said scarifying blades being positioned between said support plates, a first fastener of predetermined dimension passing through said support plates and the upper end of said scarifying blade, a second fastener of a dimension less than said predetermined dimension passing through said support plates and said scarifying blade immediately below said fastener, whereby an excess of pressure applied to said scarifying blade will shear said second fastener and pivot the scarifying blade about said first fastener.

23. The road scarifier apparatus for excavating a road surface as set forth in claim 22 further including a plurality of spring means for automatically biasing said arms upwardly to raise the scarifying blades from the road surface when the pressure applying units are de-activated.

24. The road scarifier apparatus for excavating a road surface as set forth in claim 23, wherein said spring means are a plurality of discrete leaf springs, each leaf spring associated with its associated arm means.

25. The road scarifier apparatus for excavating a road surface as set forth in claim 15, which includes fluid pressure control means associated with said yieldable pressure control means, said pressure control means having means to control the pressure of the endmost units of the scarifying blades independent of control of the units therebetween, said control means further including means for deactivating selected ones of said plurality of units including said endmost units of scarifying blades.
